US00D671643S

(12) **United States Design Patent**
Ierulli

(10) **Patent No.:** **US D671,643 S**
(45) **Date of Patent:** **** Nov. 27, 2012**

(54) **NASAL DILATOR**

(76) Inventor: **Joseph Vincent Ierulli**, Portland, OR
(US)

6,065,470 A 5/2000 Van Cromvoirt et al.
6,098,616 A 8/2000 Lundy et al.
6,196,228 B1 3/2001 Kreitzer et al.

(Continued)

(**) Term: **14 Years**

(21) Appl. No.: **29/420,787**

(22) Filed: **May 13, 2012**

Primary Examiner — Bridget L Eland

(74) *Attorney, Agent, or Firm* — Mersenne Law LLC

(57) **CLAIM**

The ornamental design for a nasal dilator, as shown and described.

DESCRIPTION

- (60) Continuation of application No. 29/399,247, filed on Aug. 11, 2011, now abandoned, which is a division of application No. 29/380,763, filed on Dec. 10, 2010, now Pat. No. Des. 659,245, which is a continuation-in-part of application No. 12/106,289, filed on Apr. 19, 2008, now Pat. No. 8,062,329.
- (51) **LOC (9) Cl.** **24-02**
(52) **U.S. Cl.** **D24/135**
(58) **Field of Classification Search** D24/133,
D24/135, 136; 606/191-199

See application file for complete search history.

FIG. 1 is a perspective view of a first embodiment of a nasal dilator showing my new design;
FIG. 2 is a top plan view thereof;
FIG. 3 is a front view thereof, the rear view being a mirror image;
FIG. 4 is a right side view thereof, the left side view being a mirror image;
FIG. 5 is a bottom plan view thereof;
FIG. 6 is a perspective view of a second embodiment of a nasal dilator showing my new design;
FIG. 7 is a top plan view thereof;
FIG. 8 is a rear view thereof;
FIG. 9 is a front view thereof;
FIG. 10 is a right side view thereof, the left side being a mirror image;
FIG. 11 is a bottom plan view thereof;
FIG. 12 is a perspective view of a third embodiment of a nasal dilator showing my new design;
FIG. 13 is a top plan view thereof;
FIG. 14 is a front view thereof, the rear view being a mirror image;
FIG. 15 is a right side view thereof, the left side view being a mirror image; and,
FIG. 16 is a bottom plan view thereof.
The broken line showing of human facial features is directed to environment and is for illustrative purposes only; the broken lines form no part of the claimed design.
